UNITED STATES PATENT OFFICE.

THOMAS M. BRINTNALL, OF MEDINA, OHIO.

VICE.

SPECIFICATION forming part of Letters Patent No. 514,614, dated February 13, 1894.

Application filed March 30, 1893. Serial No. 468,400. (No model.)

To all whom it may concern:

Be it known that I, THOMAS M. BRINTNALL, a citizen of the United States, residing at Medina, in the county of Medina and State of Ohio, have invented certain new and useful Improvements in Vises; and I do hereby declare that the following is a full, clear, and exact description of the invention, which will enable others skilled in the art to which it appertains to make and use the same.

My invention relates to improvements in vises, commonly known as bench or table vises, and the invention consists in the construction substantially as shown and described and particularly pointed out in the claims.

In the accompanying drawings, Figure 1 is partly a side elevation and partly a central sectional elevation of my improved vise, with the jaws separated, and Fig. 2 is a side elevation thereof with the jaws clamping an article between them. Fig. 3 is a front elevation of the inner removable jaw alone, and Fig. 4 is a central vertical sectional view of the lower part of the said jaw, revealing especially the form of the groove or channel therein. Fig. 5 is a cross section of the toothed supporting arm or extension of the body.

A represents the body of the vise, and B and C, respectively, the jaws thereof. The body A is formed with a jaw supporting bar or projection a, having a series of transverse teeth a', and shoulders or ribs a² lengthwise along the top thereof at the base of the teeth, and strengthening flanges a³ at either side of the bottom of the bar. Obviously, this is only one of many forms of bar or beam a that might be adopted and serve the same purpose and be within the spirit of the invention. Upon this bar, constructed throughout its length as seen in Fig. 5, I place the sliding jaw B. This jaw may be moved by hand to any desired position on the bar a, according to the size of the article to be held, and can be bodily removed therefrom and replaced with ease. Said jaw is provided with a head suited to the formation of said bar, and has flaring side grooves or channels b adapted to the shoulders a² thereof, a tooth or teeth b' to engage the teeth a', and an open slot along its bottom

to accommodate the head to the web a⁴ of the said bar. It will be noticed that the top shoulders b² of the grooves or channels b are parallel to the shoulders a² and rest thereon when the jaw B is down as in Fig. 2, which is its normal position. But the bottoms of said channels are inclined from front to rear, as seen also in Fig. 5, so that when the position of the jaw is to be changed it can be raised at its rear to clear the engaging tooth or teeth 60 substantially as seen in Fig. 1. When in this latter position the jaw is free to be moved back and forth. It will also be noticed that the channels or grooves b at their front are of such size that they afford simply a free 65 sliding movement to the jaw on the shoulders a² and do not permit any material up and down movement of the jaw at this point. This prevents the jaw from lifting or tilting up at the front when pressure is on, and causes 70 the pressure to so firmly lock tooth b' on the bar a that the jaw cannot slip or yield. Obviously the teeth or catches on the jaw and bar may be differently constructed from what are here shown and serve the same purpose. 75 Any equivalent of the construction shown may be adopted. The jaw C is pivoted at c to the body A, and at about its center has an opening c' for the passage of the binding screw E. The opening or hole c' is somewhat 80 enlarged as compared with the screw E so as to give the jaw C the requisite freedom of back and forth movement at its top, say half an inch or thereabout. It will be observed that when a piece is fastened between the two 85 jaws and the binding screw is applied, the engaging teeth of the rear jaw firmly unite with the rack teeth of the bar by compression force. Also that but a part of a turn, or one or two turns at most of the binding screw is 90 necessary to clamp the object in place, and that the strength of the vise is not weakened by the position of the sliding jaw, and that I may and do employ a finer threaded screw 95 for binding than is commonly used in bench vises.

To operate, the front jaw is supposed to stand a little out from the head of the bar. Tilt the rear jaw slightly forward till it is disengaged and shove it back; place the object 100

next to the front jaw, and draw the rear jaw up to the work and then turn the screw lever to fasten.

Having thus described my invention, what I claim is—

1. In a vise, the combination of a suitable supporting frame or bar, a rear jaw which is adapted to slide longitudinally on the frame, a front jaw pivoted at its lower end to said frame, and an operating screw for adjusting the front jaw, substantially as described.
2. In a vise, the combination of a suitable supporting frame or bar, a self-locking rear jaw which is adapted to be slid longitudinally on the said frame, a front jaw pivoted at its lower end to said frame, and an operating screw for adjusting the upper end of the front jaw, substantially as described.
3. In a vise, the combination of a supporting frame or bar provided on its upper surface with spaced locking means, a self-locking rear jaw which is adapted to be slid longitudinally on said frame, and when released to drop automatically into and be held by the locking means, a front jaw pivoted at its lower end to said frame and an operating screw for adjusting the upper end of the front jaw backward and forward, substantially as described.
4. In a vise, the combination of a support-

ing bar or frame provided on its upper surface with locking teeth or ratchets, a self-locking rear jaw provided with a tooth or pawl to engage the teeth on the frame, said jaw adapted to be slid longitudinally on the frame and when released to automatically drop into and be held by the teeth on said frame, a front jaw pivoted at its lower end to said frame and a screw which passes through the said front jaw for adjusting the upper end of the same, substantially as described.

5. In a vise, the combination of a supporting bar or frame provided with locking means for holding the rear jaw of the vise and having longitudinal flanges or shoulders, a rear jaw having grooves which engage the flanges of the frame and adapted to be slid longitudinally on said frame, a front jaw pivoted at its lower end to the frame and an adjusting screw which passes through the front jaw and enters the head of the frame for adjusting the upper end of said jaw, substantially as described.

Witness my hand to the foregoing specification this 27th day of February, 1893.

THOMAS M. BRINTNALL.
